(57) **CLAIM**

The ornamental design for a combined transmitter and clips for strap for heart rate monitor, as shown and described.

DESCRIPTION

FIG. 1 is a perspective top view of a combined transmitter and clips for strap for heart rate monitor showing my new design;

FIG. 2 is a perspective bottom view thereof;

FIG. 3 is a top view thereof;

FIG. 4 is a bottom view thereof;

FIG. 5 is a front view thereof;

FIG. 6 is a back view thereof; and,

FIG. 7 is a side view thereof, the opposite side view being a mirror image thereof.

The portions shown in broken lines are for illustrative purposes only and form no part of the claimed design.
